US00D740936S

(12) **United States Design Patent**
Kim et al.

(10) **Patent No.:** US D740,936 S
(45) **Date of Patent:** ** Oct. 13, 2015

(54) **WATER FLOSSER BASE UNIT**

(71) Applicant: **Water Pik, Inc.**, Fort Collins, CO (US)

CA 851479 9/1970
CH 502817 A 2/1971

(72) Inventors: **Hyunchul Kim**, Chicago, IL (US);
Taiwon Choi, Glenview, IL (US)

(Continued)

(73) Assignee: **WATER PIK, INC.**, Fort Collins, CO
(US)

OTHER PUBLICATIONS

(**) Term: **14 Years**

US RE27,274, Jan. 1972, Mattingly (withdrawn).

(21) Appl. No.: **29/466,137**

(Continued)

(22) Filed: **Sep. 4, 2013**

Related U.S. Application Data

(63) Continuation of application No. 29/449,265, filed on Mar. 14, 2013, now Pat. No. Des. 714,929, which is a continuation of application No. 29/449,273, filed on Mar. 14, 2013, now Pat. No. Des. 725,770.

Primary Examiner — Ian Simmons

USPC **D24/111**

CLAIM

(58) **Field of Classification Search**

We claim the ornamental design for a water flosser base unit, substantially as shown and described.

USPC D24/108, 110, 111, 121; D7/384, 386,
D7/413; D23/356, 359, 360, 362; 433/80;
601/162, 163, 165
CPC ... A61C 17/02; A61C 17/0205; A61H 13/005
See application file for complete search history.

DESCRIPTION

(56) **References Cited**

FIG. 1 is a front, left isometric view of a water flosser base unit.

U.S. PATENT DOCUMENTS

FIG. 2 is a rear isometric view of the water flosser base unit of FIG. 1.

555,588 A 3/1896 Spencer
1,278,225 A 9/1918 Schamberg
1,464,419 A 8/1923 Gill
1,498,267 A 6/1924 Hachman

FIG. 3 is a front elevation view of the water flosser base unit of FIG. 1.

(Continued)

FIG. 4 is a rear elevation view of the water flosser base unit of FIG. 1.

FIG. 5 is a right side elevation view of the water flosser base unit of FIG. 1.

FIG. 6 is a left side elevation view of the water flosser base unit of FIG. 1.

FIG. 7 is a top plan view of the water flosser base unit of FIG. 1; and,

FIG. 8 is a bottom plan view of the water flosser base unit of FIG. 1.

The broken lines showing portions of the article are included for the purpose of illustrating subject matter excluded from the claim with the broken lines and the unshaded surfaces within forming no part of the claimed design.

1 Claim, 8 Drawing Sheets
